UNITED STATES PATENT OFFICE

WILLIAM L. KNIGHT, OF GREENSBURG, INDIANA

LUBRICATOR FOR CAR JOURNALS

Application filed April 19, 1929. Serial No. 356,422.

The present invention appertains to new and useful improvements in lubrication and more particularly to a novel lubricator for car journals.

5 The principal object of the invention is to provide a lubricator for constantly lubricating the journal portion of car axles.

Another important object of the invention is to provide a lubricator for car journals 10 wherein means is provided for constantly maintaining the axle lubricated regardless of the amount of lubricant available.

Another important object of the invention is to provide a lubricator for the journal ends 15 of car axles wherein means is provided for tensionally maintaining the lubricator constantly in contact with the axle.

These and other important objects of the invention will become more apparent to the 20 reader after considering the invention as described and claimed hereinafter.

In the drawings:—

Figure 1 represents a vertical sectional view through a conventional car axle journal 25 and the present invention attached thereto.

Fig. 2 represents a vertical sectional view through the improved lubricator in association with the journal end of a car axle.

Fig. 3 represents a top plan view of the 30 lubricator showing the movable web partly broken away to disclose the position of the rolls.

Fig. 4 represents a perspective view of 35 one of the rolls.

Fig. 5 represents a fragmentary vertical transverse sectional view of the device.

Fig. 6 represents a vertical sectional detail view of the lubricator.

40 Referring to the drawings wherein like numerals designate like parts, it will be seen that the lubricator is attachable to a conventional car journal structure such as is clearly shown in Fig. 1 of the drawings.

This particular type of journal consists of 45 a housing A and mount B for the brass C, which is grooved to receive the journal portion D of the car angle E.

The invention is generally referred to by 50 the numeral 5 and includes a reservoir 6 preferably of rectangular shape in plan. The

longitudinal side walls of the reservoir are flared outwardly at their lower portion 7 while the bottom 8 is curved transversely in the manner clearly shown in Fig. 1.

The side walls have outwardly diverged 55 flanges 9 which project above the top of the receptacle and each of which is provided with an inwardly disposed longitudinal rib 10. A gasket 11, preferably of steel wool or some similar material, is interposed between the flanges 9 and the portion D of the axle in the manner shown in Fig. 1.

A pair of upper rolls 12—12 are rotatably mounted on the pin 13 extending longitudinally through the reservoir. A third roll 12 is rotatably mounted on a pin 13 in parallelism to the other rolls and in close proximity to the bottom of the reservoir. A web 14 is trained over the roll in the manner shown in Fig. 1, the lower roll serving to feed the web 65 close to the bottom of the reservoir, so that even though a small amount of oil be in the reservoir, the web will nevertheless be lubricated.

Ears 14 at the ends of the flanges 9 are attached each to one end of a coiled spring 15 which has its opposite end anchored to one side wall of the journal housing A at a point well above the lubricating device, and substantially as shown in Fig. 1.

75 It will thus be seen that the present invention embodies many novel details and furthermore, the constructing of this device from sheet metal by any of the well known forming operations will render this article a cheap item in railway rolling stock maintenance 80 in comparison to its utility.

85 It is to be understood that numerous changes in the specific shape, size, and materials may be resorted to without departing from the spirit and scope of the invention as 90 claimed hereinafter.

Having thus described my invention, what I claim as new is:—

95 1. A lubricator for car axles comprising a reservoir for containing a lubricant, and tensional means for urging the reservoir against the axle, and packing means interposed between the reservoir and the car axle.

100 2. A lubricator for car axles comprising

a reservoir for containing a lubricant, tensional means for pulling the reservoir against the axle, feed means within the reservoir for delivering lubricant from the reservoir to the axle, said means consisting of spaced rolls journaled in said reservoir and a web disposed over said longitudinally extending parallel rolls.

3. A lubricator for car axles comprising
10 a reservoir for containing a lubricant, ten-
sional means for pulling the reservoir against
the axle, feed means within the reservoir for
delivering lubricant from the reservoir to the
axle, said means consisting of a pair of upper
15 rolls within the reservoir and a lower roll
adjacent the bottom of the reservoir, and a
web trained over said rolls.

4. A lubricator for car axles comprising a
reservoir, said reservoir having a constricted
20 open top, outwardly diverging flanges at the
upper edges of the reservoir, and a packing
gasket interposed between the flanges and the
car axle.

5. A lubricator for car axles comprising
25 a reservoir, said reservoir having a construct-
ed open top, outwardly diverging flanges at
the upper edges of the reservoir, a packing
gasket interposed between the flanges and the
car axle, and tensional means for normal-
30 ly urging the reservoir and gasket against
the axle.

In testimony whereof I affix my signature.
WILLIAM L. KNIGHT.
